ELECTRICALLY OPERATED CIRCUIT INTERRUPTER

Original Filed Oct. 30, 1926

UNITED STATES PATENT OFFICE.

TALMA T. GREENWOOD, OF EAST TEMPLETON, MASSACHUSETTS, ASSIGNOR TO CON-
DIT ELECTRICAL MANUFACTURING CORPORATION, OF BOSTON, MASSACHUSETTS,
A CORPORATION OF MASSACHUSETTS.

ELECTRICALLY-OPERATED CIRCUIT INTERRUPTER.

Application filed October 30, 1928, Serial No. 145,327. Renewed November 17, 1928.

This invention relates to electric circuit interrupters of the vacuum type wherein the circuit is broken in a highly evacuated container and between separable contact members from which the occluded gases have been removed.

An object of this invention is to provide an improved arrangement of the vacuum switch and its accessory apparatus to reduce the space required for the installation of the switch and also to provide a high factor of insulation between the switch and adjacent objects.

A further object is to provide an improved mechanism for opening and closing the switch.

Another object of the invention is to provide a vacuum switch so arranged that it can carry continuously a heavy current without danger of damage to the evacuated container.

A yet further object is generally to improve the construction and operation of circuit interrupters.

25 Fig. 1 is a sectional elevation taken through a circuit interrupter embodying the invention.

Fig. 2 is a sectional detail through one of the contact members of the vacuum switch 30 and illustrating the manner of cooling the contact member.

Fig. 3 is a side elevation of the movable member of the vacuum switch.

As here shown, the circuit interrupter embodying this invention comprises a casing including a receptacle 10 which is adapted to contain a suitable insulating fluid as oil. The open top of the receptacle is normally closed by a removable cover 12 which cover comprises a switch frame that supports the essential elements of the interrupter.

The interrupter is provided with a pair of insulated terminals 14 which are carried by and extend through the cover 12 and terminate beneath the surface of the oil in the casing.

The vacuum switch forming a part of this invention is connected electrically with and is supported mechanically by said terminals 50 and said terminals constitute the sole supporting means for said vacuum switch. The vacuum switch comprises a container 16 which is of suitable dimensions and is composed of some suitable insulating material

as glass. Said container is provided with a 55 neck 18 at the bottom thereof and upwardly-extended divergent necks 20 at the top thereof. Metal caps 22 are welded to said necks 20 and form closures therefor. The vacuum switch is provided with relatively large contact members which include studs 24. Said studs are integral with said caps 22 and are extended through said necks 20 into the body of the container. The studs at the lower ends are terminated in opposed and spaced contact members 26. Said caps 22 are provided with external screw-threaded studs 28. Straps 30 are disposed over said studs and nuts 32 are screw-threaded on said studs to clamp said straps in firm mechanical and 60 electrical contact with said caps. Said straps are substantially of U-shape and the upper legs of said straps are clamped by nuts 34 to the lower ends of the terminals 14. This arrangement serves to rigidly connect the 65 vacuum switch mechanically as well as electrically with said terminals. The circuit interrupter here shown is adapted to carry a relatively large amount of current. To this end, the studs 24 are made hollow or are provided with internal passages 36 as shown 70 most clearly in Fig. 2 and said passages are open at their upper ends only and are in free communication with the body of oil contained in the enclosing casing. Cool oil is 75 adapted to flow into said passages and hot oil is adapted to flow out of said passages by thermal circulation, thereby to keep the studs cool and prevent damage to the container 16. The caps 22 and the straps 30 are also exposed to the cool body of insulating fluid in 80 which they are immersed and thus are maintained cool. The heat absorbed by the body of hot insulating fluid is ultimately given up to the surrounding atmosphere through the 85 heat-conducting walls of the oil receptacle 10.

The contact members 26 are adapted to be bridged and electrically connected by a bridging member 38. Said member is movable upwardly into engagement with said 90 bridging members to complete the circuit therebetween and is adapted to be held in the aforesaid position to maintain the circuit closed. The bridging member is adapted to be moved downwardly to interrupt the circuit. 95

The switch is electrically opened and closed. The switch operating mechanism comprises a metal tube 40 which is sealed at its lower

end and which has its upper and open end welded to the neck 18 of the container. A similar metal tube 42 is welded to the tube 40 at right angles therewith and intermediate 5 its length. A second metal tube 44 is welded in a similar manner to said tube 42 and in line with said first tube 42. The joints between the tubes 42 and 44 is such as to provide a vacuum-sealed connection therebetween. A 10 solenoid 46 constituting the closing solenoid of the switch is received on the tube 42. A solenoid 48 constituting the opening solenoid of the switch is received on the tube 44. A magnetic core or plunger 50 is received with- 15 in said tubes 42 and 44 and is reciprocable therein under the influence of said solenoids. Said plunger is adapted to be moved toward the right to open the switch and toward the left to close the switch. Said plunger is 20 adapted to reciprocate a switch-operating member or piston 52. Said piston is disposed to slide freely within the tube 40 and is connected with said bridging member 38 by means of a rod 54 of insulating material as 25 glass. Said piston is provided with a vertically-elongated slot 56 therein in which said plunger 50 is freely movable. The lower wall of said slot is given a V-shape as indicated at 58, whereby to form a cam face that is adapted 30 to be engaged by the plunger to effect the opening of the switch. The plunger 50 is provided with a notch 60 in its lower portion. The left hand edge of said notch is inclined as indicated at 62 thereby to provide 35 a cam face which is adapted to engage the corresponding cam face of the projection 58 so that the movement of the plunger and the rod serves to depress the piston 52 and thereby to open the switch. Said plunger is pro- 40 vided with a flat lower face 64 adapted to be engaged by the top or apex of the projection 58 thereby to hold the switch in open position until it is closed. A compression spring 66 is disposed under the piston and serves to 45 urge it constantly toward switch-closed position. The movement of the plunger 50 in a direction to open the switch serves to operate the piston against the action of said spring. The movement of the plunger towards switch- 50 closed position, however, serves to release the plunger for movement toward switch closed position by said spring. The terminals *a* and *b* of the opening and closing solenoids respectively may be brought out of the casing 55 through insulating bushings 68 in the cover 12.

By the arrangement here shown, the vacuum switch is supported entirely by the interrupter terminals 14. By immersing the 60 entire vacuum switch and its operating mechanism in a body of insulating liquid, adequate insulation is provided between the terminals of the vacuum switch and the mechanism so that the dimensions of the vacuum switch can be made relatively small and the apparatus 65

can thereby be quite compact. Also by immersing the vacuum switch in the body of insulating liquid, adequate insulation is provided between the switch and adjacent objects and the space required for the installation of 70 the switch is relatively moderate.

The container 16 is adapted to be evacuated to as high a degree as is practicable. All of the parts disposed within said container or in communication with the interior therein are 75 adapted to have the occluded gases removed therefrom and especially from the contact members 26. Under these conditions, a relatively large amount of energy can be interrupted rapidly for a small opening movement 80 of the bridging member 38.

My concurrently filed application, Serial No. 145,326, also discloses an oil-immersed vacuum switch wherein the vacuum switch casing is carried by insulating bushings. My 85 concurrently filed application, Serial No. 145,328, also discloses a switch wherein the contacts are separated in a high vacuum. The concurrently filed application of George A. Burnham, Serial No. 145,321, also discloses 90 an electrically-operated and oil-immersed vacuum switch. All of these applications are assigned to the assignee of this application.

I claim:

1. An electric switch having an oil containing casing, a pair of bushings rigidly carried by said casing and depending into the oil in said casing and having a pair of spaced contact members at and rigid with the lower ends of said bushings, an evacuated container surrounding and enclosing said contact members and carried by both of said bushings, and a movable bridging member disposed within said evacuated container in cooperative relation with said contact members. 95

2. An electric switch having an oil containing casing provided with a cover, a pair of bushings attached rigidly to said cover and extending upwardly thereabove and also depending downwardly into the oil in said oil receptacle, an evacuated container disposed between and beneath the lower ends of said bushings in the oil in said casing and having a pair of exposed terminals disposed beneath the lower ends of said bushings, attaching means rigidly connecting each of said terminals electrically and also mechanically with an adjacent bushing, stationary contact members connected rigidly with said terminals and extended downwardly within said 105 evacuated container approximately in the line of said bushings, and a movable bridging member disposed within said evacuated container and cooperating with said contact members, said bushings providing the sole support for said evacuated container. 115

3. An electric switch having an oil containing casing provided with a cover, a pair of bushings attached rigidly to said cover and extending upwardly thereabove and also de- 125

pending downwardly into the oil in said oil receptacle, an evacuated container disposed between and beneath the lower ends of said bushings in the oil in said casing and having a pair of exposed terminals disposed beneath the lower ends of said bushings, attaching means rigidly connecting each of said terminals electrically and also mechanically with an adjacent bushing, stationary contact members connected rigidly with said terminals and extended downwardly within said evacuated container approximately in the line of said bushings, and a movable bridging member disposed within said evacuated container and cooperating with said contact members, and operating mechanism for said bridging member carried by said evacuated container below said terminals and bridging member, said bushings constituting the sole supporting means for said evacuated container and operating mechanism.

4. A circuit interrupter comprising an evacuated container comprising a body and a pair of spaced necks upstanding thereabove, exposed terminals carried by said necks, stationary contact members connected electrically and rigidly mechanically with said necks and extended downwardly within said necks into the body of said container, a movable bridging member disposed within the body of said container in cooperative relation with said contact members and operating mechanism carried by said container at the bottom thereof and beneath said contact members and bridging member and having an operative connection with said bridging member.

5. A circuit interrupter including an evacuated container, contact members disposed within said container, at least one of which contact members is fixed to the wall of said container and extends outwardly therethrough, said fixed contact member having a passage therein which is open only outside said container, and means to maintain a circulatory body of insulating fluid in said passage.

6. A circuit interrupter including an evacuated container, contact members disposed within said container, at least one of which contact members is fixed to the wall of said container and extends outwardly therethrough, said fixed contact member having a passage therein which is open only outside said container, and means to cool said contact member including means to maintain a circulatory body of cool insulating fluid in said passage.

7. In a circuit interrupter, the combination of an evacuated container, fixed and movable contact members contained therein, said fixed contact members being extended through the wall of said container, an operating mechanism for the movable contact member including a tube connected with said

container at one end and sealed at the other end, a switch operating member reciprocable within said tube and having a connection with said movable contact member, said tube having opposed branch-tubes which are sealed at their outer ends and are in free communication with said first tube at their inner ends, closing and opening solenoids surrounding said branch-tubes, and a plunger common to both branch-tubes and having an operative connection with said switch operating member, whereby to reciprocate it.

8. In a circuit interrupter, the combination of an evacuated container, fixed and movable contact members contained therein, said fixed contact members being extended through the wall of said container, an operating mechanism for the movable contact member including a tube connected with said container at one end and sealed at the other end, a switch operating member reciprocable within said tube and having a connection with said movable contact member, said tube having opposed branch-tubes which are sealed at their outer ends, closing and opening solenoids surrounding said branch-tubes and a plunger common to both branch-tubes and having an operative connection with said switch operating member whereby to reciprocate it, and means to bias said switch operating member for movement in one direction.

9. In a circuit interrupter, the combination of an evacuated container, fixed and movable contact members contained therein, said fixed contact member being extended through the wall of said container, operating mechanism for the movable contact member including a tube connected with said container at one end and sealed at the other end, a switch operating member reciprocable within said tube and having a connection with said movable contact member, said tube having opposed branch-tubes which are sealed at their outer ends and are in free communication with said first tube at their inner ends, closing and opening solenoids surrounding said branch-tubes, a plunger common to both branch tubes and having an operative connection with said switch operating member whereby to reciprocate it, and means to bias said switch operating member for movement toward switch-closed position.

10. In a circuit interrupter, the combination of an evacuated container, fixed and movable contact members contained therein, said fixed contact members being extended through the wall in said container, operating mechanism for the movable contact member including a tube connected with said container at one end and sealed at the other end, a switch operating member reciprocable within said tube and having a connection with said movable contact member, said tube having opposed branch-tubes which are sealed at their outer ends and are in free communication

- tion with said first tube at their inner ends, closing and opening solenoids surrounding said branch-tubes, a plunger common to both branch-tubes and having an operative connection with said switch connecting member whereby to reciprocate it, and means to bias said switch operating member for movement toward switch-closed position, said plunger having means cooperating with said switch operating member to restrain it against action of its biasing means.
11. An electric switch having an oil containing casing, a pair of bushings rigidly carried by said casing and depending into the oil in said casing and having a pair of spaced contact members at the lower ends of said bushings, an evacuated container surrounding and enclosing said contact members and carried by both of said bushings,
- and a movable bridging member disposed within said evacuated container in cooperative relation with said contact members.
12. A circuit interrupter having a pair of fixed insulated terminals, and an evacuated container having stationary and movable contact members, the stationary contact members having terminal portions external of said evacuated container, said container having a mechanical connection with said insulated terminals and the exposed terminal portions and its stationary contact members being electrically connected with said insulated terminals, said insulated terminals constituting sole supporting means for said evacuated container. 35

In testimony whereof, I have signed my name to this specification.

TALMA T. GREENWOOD.
